UNITED STATES PATENT OFFICE

LESTER DAUGHERTY, OF KOKOMO, INDIANA

ILLUMINATED ORNAMENT FOR AUTOMOBILES

Application filed April 29, 1931. Serial No. 533,827.

This invention relates to certain new and useful improvements in illuminated ornament for automobiles.

The primary object of the invention is to provide an illuminated ornament for automobiles especially adapted for attachment to the cap of an automobile radiator in the form of an aeroplane motor having a screw propeller blade and radial cylinders with 10 side windows in the cylinders spanned by differently colored screens with each cylinder successively illuminated interiorly thereof with the light viewable through the screened windows.

15 A further object of the invention is to provide an illuminated ornament of the foregoing character wherein a lamp bulb within the body of the ornament is surrounded by a cylindrical rotatable shield having a side opening therein successively moved into registration with each cylinder by the screw propeller, the latter being automatically operated by air pressure therein during movement of the automobile.

20 With the above and other objects in view that will become apparent as the nature of the invention is better understood, the same consists in the novel form, combination and arrangement of parts hereinafter more fully 25 described, shown in the accompanying drawing and claimed.

In the drawing:—

Figure 1 is a front elevational view of an illuminated ornament for automobiles, constructed in accordance with the present invention, the same being illustrated as mounted upon the cap of an automobile radiator shown by dotted lines;

Figure 2 is a side elevational view of the device showing the bracket mounting between the radiator cap and ornament body;

Figure 3 is a vertical cross-sectional view taken on line 3—3 of Figure 2, showing the hollow radial cylinders in communication with the hollow body of the ornament and the rotatable shield within the ornament having a side opening successively moving into registration with the hollow cylinders; and

50 Figure 4 is a vertical longitudinal sec-

tional view taken on line 4—4 of Figure 1.

The ornament disclosed herein is in the simulation of an aeroplane motor comprising a body of torpedo-like formation with radial cylinders and a forwardly positioned propeller, the reference numeral 5 designating the central body portion of the ornament with a conical rear end 6 attached to the central body portion as at 7 and a forward conical nose end 8 attached thereto in a manner described and carrying radial propeller blades 9.

The central body portion 5 is of hollow formation and is provided with an annular series of spaced threaded openings into which radial cylinders 10 are threaded, the cylinders 10 representing the cylinders of an aeroplane motor, being in open communication at their inner ends with the interior of the annular hollow body 5 while the outer ends of the cylinders 10 are closed as illustrated. The front and rear sides of each cylinder 10 are provided with openings or windows 11 between the inner and outer ends thereof and each cylinder 10 has a colored transparent or translucent screen 12 therein extending over the windows 11, the screens of the several cylinders differing in color.

The illuminating means associated with the ornament includes a lamp socket 13 supported in a cross wall 14 at the forward end of the tail portion 6 of the ornament while the lamp or bulb 15 set into the socket 13 extends into the hollow body portion 5, an electrical conductor 16 extending from a source of energy 85 to the lamp socket 13.

The conical nose 8 of the motor body is provided with an inner central boss 17 into which a bearing pin 18 is threaded, the bearing pin extending through a roller bearing 19 set in the forward end wall 20 of the hollow body portion 5. The inner end of the pin 18 extends into the hollow body portion 5 and is anchored to the closed end wall 21 of an annular shield 22 that surrounds the lamp 15, 95 the shield 22 being of a diameter less than the internal diameter of the hollow body portion 5 and being rotatable within the body portion by its rigid connection with the pin 18 that is fixed to the propeller nose 8. A single 100

opening 23 is provided in the annular shield 22 and upon rotation of the shield with the nose 8, the opening 23 is successively brought into registration with the several radial cylinders.

The ornament is attached to a bracket arm 24 by fastening devices 25 and said bracket is adapted to be secured to the cap C of the automobile radiator R illustrated by dotted lines 10 in Figures 1 and 2 by means of a screw pin and nut connection 26.

From the above detailed description of the invention, it is believed that the construction and use thereof will at once be apparent, it 15 being noted that during the forward travel of the automobile, air pressure upon the blades 9 causes rotation of the nose 8, pin 18 and shield 22 carried by the pin. When the lamp 15 is illuminated, light rays therefrom 20 are successively directed into the several cylinders 10 as the opening 23 in the side wall of the shield 22 is brought into registration with the cylinder. As a differently colored screen 12 is arranged in each of the cylinders, attractive light effects are produced and tend to 25 create the impression of firing within the cylinders and producing a more realistic effect of an aeroplane motor.

While there is herein shown and described 30 the preferred embodiment of the invention, it is nevertheless to be understood that minor changes may be made therein without departing from the spirit and scope of the invention as claimed.

35 I claim:—

1. In an illuminated ornament of the character described, a body portion, radial cylinders carried by the body, a rotatable propeller blade at the forward end of the body, illuminating means within the body, rotatable means operated by the propeller to effect successive illumination of the cylinders, each cylinder having side windows therein, and a colored screen in the cylinder spanning the windows.

2. In an illuminated ornament of the character described, a body portion, radial cylinders carried by the body, a rotatable propeller blade at the forward end of the body, 50 illuminating means within the body, means operated by the propeller to effect successive illumination of the cylinders, including a shield inclosing the illuminating means and having a side opening successively registering with the cylinders, each cylinder having side windows therein, and a colored screen in the cylinder spanning the windows.

3. In an illuminated ornament of the character described, a body portion, radial cylinders carried by the body, a rotatable propeller blade at the forward end of the body, illuminating means within the body, and rotatable means operated by the propeller to effect successive illumination of the cylinders, including a shield inclosing the illuminating means

and having a side opening successively registering with the cylinders, each cylinder having side windows therein, and a colored screen in the cylinder spanning the windows.

In testimony whereof I affix my signature. 70

LESTER DAUGHERTY.
